DESIGN FOR AN AIR CONDITIONING CONTROL

Henry Dreyfuss, New York, N. Y., assignor to
Minneapolis-Honeywell Regulator Company,
Minneapolis, Minn., a corporation of Delaware

Application July 19, 1935, Serial No. 57,729

Term of patent 14 years

To all whom it may concern:

Be it known that I, Henry Dreyfuss, a citizen of the United States, residing at 501 Madison Ave., city of New York, in the county of New York and State of New York, have invented a new, original, and ornamental Design for Air Conditioning Control, of which the following is a specification, reference being had to the accompanying drawing, forming part thereof, and in which

Figure 1 is a perspective view of an air conditioning control embodying my new design looking from the top and to the left; and

Figure 2 is a perspective view of the same looking from below and to the right.

I claim:

The ornamental design for an air conditioning control, substantially as shown.

HENRY DREYFUSS.
